Primary Examiner—Wallace R. Burke**Assistant Examiner—Joel Sincavage****Attorney, Agent, or Firm—Gerald M. Newman****[57] CLAIM**

The ornamental design for a flatpack capacitor, as shown and described.

DESCRIPTION

FIG. 1 is a front and upper left perspective view of a flatpack capacitor showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

FIG. 1

FIG. 3

FIG. 4

FIG. 6

FIG. 5

FIG. 7
